UNITED STATES PATENT OFFICE.

JOSEPH PAUPA AND GUSTAV F. HOCHRIEM, OF CHICAGO, ILLINOIS.

DESIGN FOR A VENDING-MACHINE CASING.

51,389.

Specification for Design.

Patented Oct. 16, 1917.

Application filed August 27, 1917. Serial No. 188,536. Term of patent 14 years.

To all whom it may concern:

Be it known that we, JOSEPH PAUPA and GUSTAV F. HOCHRIEM, both citizens of the United States, residing in Chicago, in the county of Cook, in the State of Illinois, have invented a new, original, and ornamental Design for Vending-Machine Casings, of which the following is a specification, reference being had to the accompanying drawing, forming part thereof.

The figure of the drawing illustrates our vending machine casing in perspective.

What we claim is:—

The ornamental design for a vending machine casing, as shown.

JOSEPH PAUPA.

GUSTAV F. HOCHRIEM.

Witnesses:

STANLEY W. COOK,

LORETTA M. GIBBONS.
